UNITED STATES PATENT OFFICE.

LOUIS W. WORSHAM, OF HOUSTON, TEXAS.

DRAFT ATTACHMENT FOR MOTOR-VEHICLES.

1,378,575.

Specification of Letters Patent.

Patented May 17, 1921.

Application filed January 20, 1920. Serial No. 352,820.

To all whom it may concern:

Be it known that I, LOUIS W. WORSHAM, a citizen of the United States, residing at Houston, in the county of Harris and State 5 of Texas, have invented certain new and useful Improvements in Draft Attachments for Motor-Vehicles, of which the following is a specification.

This invention relates to new and useful 10 improvements in a draft attachment for motor vehicles.

One object of the invention is to provide a device of the character described by means 15 of which the vehicle may pull itself free when its traction wheels have become embedded in a soft or muddy road.

Another object of the invention is to provide a device of the character described which may be readily applied to a motor 20 vehicle and which may be utilized by the driver in the seat of the vehicle through a draft cable employed.

A further feature of the invention resides in the provision of an appliance of 25 the character described, which is simple in construction and which may be cheaply manufactured and easily applied to the vehicle.

With the above and other objects in view, 30 the invention has particular relation to certain novel features of construction, operation and arrangement of parts, an example of which is given in this specification and illustrated in the accompanying drawings 35 wherein,

Figure 1, shows an enlarged side elevation of the motor of the vehicle mounted in the frame thereof and showing the device applied to the vehicle,

Fig. 2, is a fragmentary front elevation 40 of the vehicle,

Fig. 3 is a fragmentary plan view thereof,

Fig. 4, shows an enlarged plan view of a drum employed, and

Fig. 5 shows an enlarged front end view 45 thereof showing the bracket therefor.

Referring now more particularly to the drawing wherein like numerals of reference 50 designate similar parts in each of the figures, the numeral 1 designates the motor, and the numeral 2 refers to the radiator. The forward end of the motor crank shaft is formed into a clutch member 3 which is aligned with the crank bearing 4 through the 55 lower part of the radiator. Extending

through this bearing there is a short shaft 5, whose outer end has the drum 6 fixed thereon and whose inner end is formed to engage with said clutch member 3. This shaft is normally held out of engagement 60 with said clutch member by means of the coil spring 7 which surrounds said shaft and which presses against the inner end of the drum 6. A U-shaped bracket 8 is secured to the front end of the vehicle and 65 embraces said drum 6 and this bracket has a bearing 9 provided to receive the end of the crank 10. The outer end of the shaft 5 is formed with ratchet teeth and the adjacent end of the crank 10 is correspondingly 70 formed, said teeth intermeshing to clutch the crank with said shaft when it is desired to rotate the shaft. When it is desired to start the motor the crank 10 is applied in the usual way and the shaft 5 is 75 forced inwardly into engagement with the clutch member 3, the drum 6 having sufficient play between the bracket 8 and the vehicle body to permit this movement. When the crank is now turned the motor 80 will start in the usual manner. Should the vehicle become stuck on muddy or slippery roads, a cable 11 is employed. This cable is wound around the drum 6 and one end is passed around the pulley 12, which is supported by a suitable bracket 13 attached to one side of the vehicle frame, and said end of said cable is then fastened to a stationary object in front of the car. The other end of the cable is passed through the eye 14 at the 85 top of the radiator and extends back to within reach of the driver. The shaft 5 is then forced into engagement with the clutch member 3 and secured therein in some suitable manner, as by means of a pin 15. 90 The motor is then started through the instrumentality of the crank 10, thus rotating the drum 6. A pull exerted by the driver on the cable, causes same to grip and hold said drum and the vehicle will thereby be 95 forced to move forwardly until it has freed itself and has reached firm road.

What I claim is:—

The combination with a motor vehicle having a motor, the forward end of whose 105 crank shaft is formed into a clutch member, a drum shaft, one end of which is adapted to be connected with and disconnected from said clutch member, a drum fixed to said shaft, a pulley carried by said 110

vehicle, a cable bearing also carried by said vehicle, a cable wound around said drum, one end of which passes around said pulley and is attached to a stationary object and the other end of which passes through said cable bearing and is free.

5 In testimony whereof I have signed my

name to this specification in the presence of two subscribing witnesses.

LOUIS W. WORSHAM.
